[57] ABSTRACT

Crane trolley comprising stub axle mounted wheels which are resiliently spaced from the supporting frame. The rollers may be hollow, and contain oil boxes, bearings, and spacing springs.

SPRING CENTERING CRANE TROLLEY WHEELS

SUMMARY OF THE INVENTION

This invention relates to trolleys for use in various types of cranes.

The primary object of the present invention is to provide trolleys for various types of cranes in which the pulleys are not subjected to equal wear.

In conventional cranes, such as overhead travelling cranes, jib cranes and post cranes, the trolleys have the following defects. For instance, in the trolleys for overhead traveling cranes, the introduction of grease into a bearing is impossible because a driving roller and a free roller do not have hollow portions, since they are made in one piece. Besides, in the case of overhead travelling cranes, the guide rail may bend even though they are designed to be straight. Consequently either the left front and rear rollers or the right front and rear rollers which move back and forth on the guide rail encounter excessive resistance and excessive wear.

These and other objects and advantages of this invention will be better understood upon consideration of the following detailed description and the accompanying drawings in which:

FIG. 1 is a top plan view showing a first embodiment of a trolley according to this invention suitable for use in various types of crane;

FIG. 2 is a vertical section taken along the line II—II of FIG. 1;

FIG. 3 is a vertical section taken along the line III—III of FIG. 1;

FIG. 4 is a vertical section taken along the line IV—IV of FIG. 1;

FIG. 5 is a top plan view showing a second embodiment of a trolley according to this invention suitable for use in various types of crane;

FIG. 6 is a vertical section taken along the line VI—VI of FIG. 5;

FIG. 7 is a top plan view showing a third embodiment of trolley according to this invention suitable for use in various types of crane;

FIG. 8 is a left side view of the trolley shown in FIG. 7;

FIG. 9 is a right side view of the trolley shown in FIG. 7;

FIG. 10 is a vertical section taken along the line X—X of FIG. 8;

FIG. 11 is a vertical section taken along the line XI—XI of FIG. 8; and

FIG. 12 is a top plan view showing a change in position of the trolley constituting the third embodiment of the invention.

Referring now to FIGS. 1—4, the first embodiment of this invention, the front of which is at the right of these figures, will now be described.

Front shaft 2 and rear shaft 3 are mounted at the front and the rear respectively of frame 1.

The front roller comprises a left half 4 and a right half 5 mounted on the shaft 2. A driving gear 6 is attached to the right side of the right roller-half 5, and the left half 4, the right half 5 and the driving gear 6 are fastened together by the bolts 7. The roller is provided with a peripheral groove 8, and an oil box 9 is formed inside it. Ball bearings 10 and 11 are mounted on the front shaft 2 on both sides of the oil box 9, and a pair of springs 12 and separator 13 are positioned between the bearings 10 and 11. The inner end of each spring 12 bears against a collar 2a fixed to the shaft 2.

The rear roller comprises a left half 15 and a right half 16 connected together by bolts 14 and mounted on the rear shaft 3. This roller is provided with a peripheral groove 17 and an oil box 18 is formed inside it. Ball bearings 19 and 20 carried by the rear shaft 3 are mounted on opposite sides of the oil box 18, and a pair of springs 21 and separator 22 are positioned between the bearings 19 and 20. The inner end of each spring 21 bears against a collar 3a fixed to the shaft 3. Bores 23 and 24 in the front shaft 2 and rear shaft 3 respectively communicate with the oil boxes 9 and 18, respectively.

Reference numerals 25 and 26 indicate grease cups which are mounted at the ends of the bores 23 and 24 respectively.

In this embodiment, since the driving roller to be mounted on the front side shaft 2 comprises the left half 4, the right half 5 and the driving gear 6, and the free roller comprises the left half 15 and the right half 16, a rather large space is available for the oil boxes 9 and 18 in the centers of the rollers. Consequently the pairs of ball bearings 10, 11, and 19, 20 can be inserted in the oil boxes 9 and 18 respectively so that the trolley can operate smoothly and last for a long time.

The second embodiment of this invention will now be described. As shown in FIGS. 5 and 6, the front of the device is at the left of the figures and front shaft 32 and rear shaft 33 are mounted at the front and the rear of trolley frame 1. The left roller half 34 and right roller half 35, which are biased together by springs 36 and 36', are mounted on the front shaft 32. The driving gear 27 is mounted on the right side of the right roller half 35, and the left roller half 34, the right roller half 35 and the driving gear 27 are fastened together by bolt 28. This roller is provided with a peripheral groove 29 and an oil box 30 is formed inside the roller. Ball bearings 31 and 31' which are mounted on the front side shaft 32 are positioned on both sides of the oil box 30, and spaced by separator 39. A bore 40 which communicates with the oil box 30 is provided in the front side shaft 32. Reference numeral 41 indicates a grease cup which is inserted into the end of the bore 40. The rear roller is composed of the two halves 37, 38 and mounted on the shaft 33, and is identical to the front roller, except for the omission of the driving gear.

In this second embodiment, since the driving roller mounted on the front shaft 32 comprises the left half 34, the right half 35 and the driving gear 27, and the free roller comprises the left half 38 and the right half 37, a rather large space is available for the oil boxes in the center. Consequently the pairs of ball bearings may be inserted in the oil boxes so that the trolley can operate smoothly and last for a long time. Moreover, since the roller comprising the left half 34 and the right half 35, and the roller comprising the left half 38 and the right half 37 respectively can slide slightly to the left or right on their respective shafts, against the resistance of the springs 36, 36', the rollers can adapt to the condition of the rails. Accordingly, even when the rails are not straight but are somewhat uneven, the rollers do not wear excessively.

The third embodiment of this invention will now be described. As shown in FIGS. 7—12, the left front horizontal shaft 62 and left rear horizontal shaft 63 are mounted at the same height at the front and the rear of the upper part of left frame 61. Right front horizontal shaft 62' and right rear horizontal shaft 63' are mounted at the front and the rear of the upper part of right frame 61'. A drive shaft 44 is mounted at the upper center of the left frame 61, and front horizontal bolt 45 and rear horizontal bolt 46 connect the lower parts of frames 61 and 61'. The horizontal bolt 48 passing through the right frame 61' is attached to the middle of the supporting plate 47, which is attached to the lower part of the right frame 61', and the right ends of the left front horizontal bolt 45 and the left rear horizontal bolt 46 are located at the front and rear of the supporting plate 47. Left front flanged roller 64 and left rear flanged roller 65 are mounted on the left front horizontal shaft 62 and the left rear horizontal shaft 63 respectively, and right front flanged roller 75 and right rear flanged roller 76 are mounted on the right front horizontal shaft 62' and the right rear horizontal shaft 63' respectively. Left front spring 72 is mounted between the left frame 61 and the left front roller 64, and left rear spring 73 is mounted between the left frame 61 and the left rear roller 65. Right front spring 72' is provided between the right frame 61' and the right front roller 75, and right rear spring 73' is provided between the right frame 61' and the right rear roller 76. Driving gear 49 provided at the inner end of the drive shaft 44 engages front gear 50 and rear gear 51 which are connected to the outside of the left front roller 64 and left rear roller 65 respectively. Motor 52 is mounted at the outer end of the driving shaft 44.

In FIGS. 9—11, reference numeral 53 indicates a guide rail. In this third embodiment, if the right front roller 75 and right rear roller 76 are positioned on the right side of the guide rail

53, the trolley comprising these pulleys may be put on the guide rail 53 with perfect freedom of motion. In this case, the left front roller 64 and the left rear roller 65 are driven on the left side of guide rail 53 through the drive shaft 44, driving gear 49, the front gear 50, and the rear gear 51, by the motor 52. Accordingly the trolley can advance and the right front roller 75 and the right rear roller 76 are driven along the right side of the guide rail 53. When the left front and rear rollers or right front and rear rollers are rotated, if the guide rail 53 bends or curves, for instance, pressure is exerted on the flange of the left front roller 64 by the bending of the guide rail 53, and the left front spring 72 presses against the front portion of the left frame 61 while being compressed. But the width of the left side and right side portions of the guide rail 53 are equal at all times even if the guide rail bends or curves. Therefore, a gap is produced between the flange of the right front roller 75 and the right portion of the guide rail 53. However, the front portion of the left frame 61 turns slightly to the left when it is urged to the left. Consequently, as the front portion of the frame 61 turns to the left with the motion of the frame 61 and presses against the right front roller 75 through the right front spring 72' thus causing it to move to the left. The flanges of the left front roller 64 and the right front roller 75 then come in contact with both side portions of the guide rail 53 under normal pressure. If the left portion of the guide rail 53 presses against the flange of the left rear roller, the right rear roller 16

moves with it. If the right hand portion of the guide rail 53 presses against the flange of the right front roller 75, the left front roller 64 moves with it. If the right-hand portion of the guide rail 53 presses against the flange of the right rear roller 76, the left rear roller 65 moves with it. Consequently, all four rollers of the trolley may press against the side portions of the guide rail 53 with normal contacting pressure at all times, in spite of the fact that the guide rail 53 bends or curves. The trolley can therefore move back and forth smoothly and abrasion of the four rollers is remarkably decreased.

What is claimed is:

1. In a trolley for cranes and the like including a support comprising a frame and at least two parallel shafts mounted in said frame, the improvement which comprises a hollow roller rotatably mounted on each shaft, each roller comprising two coaxial parts defining a central recess, abutment means on each shaft positioned centrally of the recess in the roller carried by that shaft, resilient means in each recess spacing each part of the roller defining that recess from said abutment, and means for admitting a lubricant into said recess.

2. Trolley as claimed in claim 1 comprising bearing means in each recess rotatably mounting each roller on its respective shaft and positioned between said resilient means and each part of said roller.
